ABSTRACT OF THE DISCLOSURE

A hand-held device for wringing liquids from articles, for example the bristles of paint brushes or the like, comprising a substantially U-shaped handle having bristle-engaging members projecting laterally of the handle from the ends of the legs of the U and located at one side of the handle, which legs are normally yieldingly urged to position the members in spaced relation to enable the bristles to be disposed between them and to be moved into engagement with the bristles by the gripping action of the hand on the legs of the U to move them toward one another and to remove material from the bristles as the device is thereafter moved along the bristles.

Heretofore it has been the practice to wipe the bristles of a paint brush on the side of the opening in a paint container to remove material from the bristles. Where wringer devices have been provided they have been built-in, or made a part of, or have been secured to the container. The prior arrangements have not been entirely satisfactory and have been restrictive in their use.

The present invention provides a hand-held wringing device which is portable and readily effective for removing paint or other material from the bristles of a paint brush or from other articles from which it is desired to remove liquid material.

This is accomplished by a readily portable hand-held device having a substantially U-shaped handle provided at the free ends of the legs of the U with cooperating laterally projecting contact elements located to one side of the handle and which are normally and yieldably held in spaced relation to readily receive between them the bristles of a brush or other article from which it is desired to wring liquid material. The contact members are then moved into engagement with the bristles by the gripping of the handle by one hand so as to move the legs of the U-shaped handle toward one another. Thereafter the contact members are drawn along the bristles to wring the liquid material from the bristles.

The contact members may be rollers or wiper arms having rounded or rolled edges thereon and the handle can comprise relatively narrow straight legs connected by a spring bow and which can be encircled by a hand in the gripping operation, or can be a relatively broad hand-receiving resilient band forming curved, spaced-apart legs connected by a bow portion with the legs providing a broad hand-engaging grip to be grasped by the hand to move the ends of the legs toward one another.

Other features and advantages of the invention will be apparent from the specification and claims when considered in connection with the accompanying drawings in which:

FIGURE 1 is a perspective view of a wringing device of the present invention.

FIG. 2 is a side view of the wringing device of FIG. 1.

FIG. 3 is a top view partly in section of the device of FIG. 1.

FIG. 4 is a front view of the device of FIG. 1 showing a paint brush in position.

FIG. 5 is a view similar to FIG. 1 showing another form of the invention.

2

FIG. 6 is a view similar to FIG. 1 showing still another form of the invention.

FIG. 7 is a front view of FIG. 6.

As shown in the drawings, the device of the present invention is a simple device for wringing a liquid from an article and which is readily portable and capable of being held and operated by one hand. For the purpose of illustrating the invention it will be described in its preferred used of wringing paint from the bristles of a paint brush.

In the form of the invention shown in FIGS. 1-4, the device comprises a substantially U-shaped handle 10 including the elongate relatively narrow legs 11, 12 connected at one end by a resilient bow portion 13, preferably of spring steel.

A pair of contact members 14, 14a are carried by the free ends of the legs 11, 12 and project laterally of the handle so as to be located at an angle to and at one side of the handle 10. The contact members in this form of the invention comprise rollers 15, 16 rotatable on shafts 17, 18. The shafts are mounted on the free ends of the legs 11, 12 by having portions disposed within sleeves 19, 20. The sleeves 19, 20 are carried by the legs 11, 12 and may be integral therewith or welded thereto.

Stop means is carried by the free ends of the shafts 17, 18 to hold the rollers thereon. While this may take various forms, as shown in FIGS. 1 and 3 it comprises portions 21, 22 crimped from the shafts 17, 18 with washers 23, 24 interposed between the crimp and the end of the roller. Washers 25, 26 are disposed between the rollers and the adjacent end of the sleeve insuring free rotation of the rollers on the shaft. The ends of the shafts project from the other end of the sleeve and are threaded to receive the lock nuts 27, 28. With this construction it will be seen that the elements of the device can be readily made and assembled.

As shown in FIGS. 1 and 4, the spring bow 13 yieldably holds the ends of the legs and the rollers carried thereby in a normal spaced relation so that a paint brush A can be readily inserted with its bristles B disposed between the rollers 15, 16 as shown in FIG. 4. The hand encircles the legs 11, 12, which are located to one side of the bristles, and in response to a gripping action thereon moves the rollers in the direction of the arrows in FIG. 4 to the dotted position in which they grip the bristles. The wringing device is then moved along the bristles to the free end thereof and will wring the paint therefrom. This only requires the use of one hand and frees the other hand to hold the paint brush if desired. Since the contact members are located to one side of the handle, this can be done without soiling the hand. As soon as the grip is released the rollers automatically move to their normal spread position.

If desired, means can be provided for limiting the movement of the legs as they move toward one another to prevent engagement or binding of the rollers. While this may take many forms, as herein illustrated in FIGS. 1 and 3, it comprises a blocking member 29 carried by sleeve 19 and positioned to engage sleeve 20 just prior to the engagement of the rollers so that undue pressure cannot be applied to the end of the rollers and cause them to skew.

The form of the invention shown in FIG. 5 is similar to that shown in FIGS. 1-4 except that the contact members are formed as rigid wipers. In this form the substantially U-shaped handle 10a has elongate narrow legs 11a, 12a connected by the resilient bow 13a. Secured to the free ends of the legs is a pair of rigid wipers 25, 26 which are curled or rolled as at 25a, 26a to apply a wringing and/or wiping action to the bristles when the handle portions 11a, 12a are gripped by one hand and move towards one another and then move along the bristles.

In the form of the invention shown in FIGS. 6 and 7, the handle 10b comprises a broad resilient band, preferably of spring steel, shaped as shown to provide curved legs 11b, 12b and the bow 13b. The free ends of the legs are spaced as shown and provided with a hollow bead forming sleeves 19b, 20b in which are mounted shafts 17b, 18b so as to project laterally from one side of the handle, as shown in FIG. 6, and carry wringing rollers 15b, 16b, which shafts are held in position by lock nuts 27b, 28b. As shown in FIG. 7 the rollers and free ends of the legs 11b, 12b are in normally spaced relation and by gripping the handle, preferably by one hand, so as to move the ends of the legs toward one another the rollers can be moved into engagement with bristles of a paintbrush and the paint wrung therefrom in response to moving said rollers over the bristles.

It will be seen, therefore, that the present invention provides a hand-held wringing device which is easily made and/or assembled, is simple to operate with one hand, and is readily portable as required.

I claim:

1. A hand-held wringing device for the bristles of paint brushes and the like articles from which liquid is to be removed comprising a substantially U-shaped handle of resilient material having brush contacting members connected to the free ends of the legs of the U with said contacting members projecting at substantially right angles to and disposed laterally of the handle to be located on one side of the handle, said handle urging and yieldably holding said contacting members in a normal spaced relation to have a brush disposed therebetween and moving said members from said normal position into wringing relation with the brush in response to gripping pressure of the hand applied to the legs of the U-shaped handle whereby material is thereafter wrung from the bristles in response to movement of the contacting members over said bristles.

2. The invention as defined in claim 1 wherein blocking means is provided for limiting the inward movement of the legs in wringing position.

3. The invention as defined in claim 1 wherein the U-shaped handle is made from resilient spring material.

4. The invention as defined in claim 1 wherein the bow portion of the U-shaped handle is made of resilient spring material.

5. The invention as defined in claim 1 wherein the contacting members comprise rollers mounted on the free ends of a pair of laterally projecting shafts, each shaft having the other end secured to the free end of a leg of the U-shaped handle.

6. The invention as defined in claim 5 wherein said handle comprises a broad strip forming curved, spaced-apart legs and a bow connecting one end of said legs, the free end of the legs having means for securing the shafts thereto, said legs providing a broad, hand-engaging grip to be grasped by a hand for moving the free ends toward one another to move the contact elements into wringing relation with the bristles.

7. The invention as defined in claim 1 wherein the contacting members comprise a pair of wiper arms, each having one end connected to the free end of a leg of the U-shaped handle, said wiper arms having a rounded bristle-engaging edge thereon.

8. The invention as defined in claim 1 wherein said handle comprises narrow legs, each connected at one end to a bow portion, said narrow legs providing a grip portion adapted to be encircled by one hand and gripped thereby to move said legs toward one another and said contact members into wringing engagement with the bristles.
